CONVERTIBLE VALVE FOR VACUUM RELEASE
OR PRESSURE RELIEFClarence B. Coleman and Harry R. Kattelmann, Oakland,
Calif.; said Kattelmann assignor to Fabricated Metals,
Inc.

Filed Aug. 20, 1970, Ser. No. 24,608

Term of patent 14 years

Int. Cl. D23—01

U.S. Cl. D23—19

FIG. 1 is a perspective view of a convertible valve for vacuum release or pressure relief embodying our new design;

FIG. 2 is a bottom plan view thereof;

FIG. 3 is a side elevation thereof; and

FIG. 4 is a top plan view thereof.

We claim:

The ornamental design for a convertible valve for vacuum release or pressure relief, as shown.
